UNITED STATES PATENT OFFICE.

JOHN W. MEANS, OF TOWANDA, PENNSYLVANIA.

BALE-TIE.

SPECIFICATION forming part of Letters Patent No. 244,140, dated July 12, 1881.

Application filed June 13, 1881. (No model.)

To all whom it may concern:

Be it known that I, JOHN W. MEANS, a citizen of the United States of America, residing at Towanda, in the county of Bradford and State of Pennsylvania, have invented certain new and useful Improvements in Cotton-Bale Ties; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to an improvement in bale-ties; and it consists in the peculiar construction and arrangement of parts, as will be more fully described hereinafter, whereby a cheap, strong, and efficient fastening is produced; and it further consists in the peculiar manner of securing the ends of the band to the fastening device.

The accompanying drawings illustrate my invention.

20 Figure 1 is a top-plan view of my device as fastened. Fig. 2 is a longitudinal sectional view of the same, showing the manner of attaching the ends of the band thereto. Fig. 3 is a side elevation of the parts detached ready 25 to go together.

A represents the buckle or fastener, which consists of the two pieces *b* *c*, both parts being provided at their outer ends with the cross-bars *k* *k*, the slots *e* *e*, the intermediate cross-bars, *l* *l*, and large openings or slots *d* *d*, as shown. At one end the part *b* is provided with the raised stud *f*, which is preferably made rectangular in shape, but may be of any other form desired. This stud fits in a corresponding opening, *g*, made in the part *c*, the said parts, when fastened, being in a line with each other, and presenting a plain unbroken surface at top and bottom, as shown in Fig. 2. In order to prevent the parts from becoming 30 detached after the band has been stretched around the bale and fastened, the stud *f* has pivoted upon it the button *h*, which is turned at right angles to the part *b*, so as to extend across the face of the part *c*, as shown in 35 Fig. 1.

40 B represents the band, which is made of the proper length to go around the bale. In securing the band to the buckle one end is passed through the large slot *d*, bent over the

outer end of the buckle, as at *k*, from whence 55 it is carried backward and upward through the slot *e*, under the portion of the band previously bent, around the cross-bars *l*, and brought forward between the top of the main portion of the band and the bottom of the buckle, as 60 shown in Fig. 2. By thus securing the ends of the band to the portions of the buckle (the other end of the band being similarly fastened to the other part of the buckle) a fastening is formed which is simple, easily and 65 quickly done, and which will resist any pressure exerted upon the band, as will readily appear from an inspection of the drawings.

Having thus described my invention, what I claim, and desire to secure by Letters Patent, is—

1. The buckle or fastener *A*, made in two pieces, both provided with the slots *d* *e* and cross-bars *k* *l*, the part *b* being provided with the stud *f*, and the button or equivalent device *h*, which are adapted to be inserted through the opening *g* made in the part *c*, the two pieces being fastened together by turning the button at right angles thereto, substantially as shown and described. 75

2. The means of fastening the band to the buckle, as described, by passing the ends through the slots *d* *d*, over the cross-bars *k* *k*, and up through the slots *e* *e*, around the cross-bars *l* *l*, the ends being then brought forward, 85 so as to terminate between the under sides of the ends of the buckle and the top surface of the band, substantially as set forth.

3. The buckle or fastener *A*, made in two pieces, both provided with the slots *d* *e* and 90 cross-bars *k* *l*, the part *b* being provided with the stud *f* and the button *h*, which are adapted to be inserted through the opening *g* made in the part *c*, in combination with the band *B*, the band being fastened thereto by passing its 95 ends through the slots *d* *d*, over and around the cross-bars *k* *k*, and up through the slots *e* *e*, around the cross-bars *l* *l*, the ends being then brought outward, so as to terminate between the under sides of the ends of the buckle 100 and the top surface of the band, substantially as set forth.

In testimony whereof I have affixed my signature in presence of two witnesses.

JOHN WILLIAM MEANS.
